US00D934403S

(12) **United States Design Patent** (10) Patent No.: **US D934,403 S**
Lei (45) Date of Patent: **** Oct. 26, 2021**

(54) **HUMIDIFIER**

(71) Applicant: **MIDEA GROUP CO., LTD.**,
Guangdong (CN)

(72) Inventor: **Hanqiang Lei**, Guangdong (CN)

(73) Assignee: **MIDEA GROUP CO., LTD.**, Foshan
(CN)

(**) Term: **15 Years**

(21) Appl. No.: **35/509,911**

(22) Filed: **May 8, 2020**

(80) **Hague Agreement Data**

Int. Filing Date: **May 8, 2020**

Int. Reg. No.: **DM/209411**

Int. Reg. Date: **May 8, 2020**

Int. Reg. Pub. Date: **Jul. 31, 2020**

(30) **Foreign Application Priority Data**

Dec. 25, 2019 (CN) 201930726409.5

Bockius LLP

(57) **CLAIM**

The ornamental design for a humidifier, as shown and
described.

DESCRIPTION

1.-3. Humidifier

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

3.1 : Front

3.2 : Back

3.3 : Left

3.4 : Right

3.5 : Top

3.6 : Bottom

3.7 : Perspective

3.8 : Front view of state of change

3.9 : Back view of state of change

3.10 : Left view of state of change

3.11 : Right view of state of change

3.12 : Top view of state of change

3.13 : Bottom view of state of change

3.14 : Perspective view of state of change

1 Claim, 28 Drawing Sheets
